UNITED STATES PATENT OFFICE.

GEORGE H. ROLFES, OF ST. LOUIS, MISSOURI, ASSIGNOR TO HANDLAN-BUCK MANUFACTURING COMPANY, OF ST. LOUIS, MISSOURI, A CORPORATION.

FONT FOR LAMPS OR LANTERNS.

SPECIFICATION forming part of Letters Patent No. 787,644, dated April 18, 1905.

Application filed April 2, 1904. Serial No. 201,335.

To all whom it may concern:

Be it known that I, GEORGE H. ROLFES, a citizen of the United States, residing in the city of St. Louis, in the State of Missouri, have invented certain new and useful Improvements in Fonts for Lamps or Lanterns, of which the following is a full, clear, and exact description, reference being had to the accompanying drawings, forming part of this specification.

My invention relates to a combined main and auxiliary font particularly intended for use in lamps or lanterns utilized for railway purposes, the object of the invention being to furnish, in connection with the main or burner font of a lamp or lantern, an auxiliary font by which the main font is replenished when the supply therein becomes diminished.

The invention consists in features of novelty hereinafter fully described, and pointed out in the claims.

Figure I is a perspective view of a railway-switch lamp, partly broken out, and my improved font shown therein. Fig. II is a perspective view of the main and auxiliary fonts shown in separated condition. Fig. III is a vertical longitudinal section taken through the main and auxiliary fonts. Fig. IV is a horizontal section taken on line IV-IV, Fig. I.

Referring first to Figs. I to IV, inclusive, A designates a switch-lamp provided with the usual semaphore-lenses B.

1 designates a main font in which is seated the burner 2. In the top of the main font is an aperture 3, and mounted on said top is a vent-nipple 4, through which the gas generated from the oil in the font may find escape.

5 designates perforations in the top of the main font, that have communication with a tube leading downwardly therethrough and through which fresh air is permitted to pass into the interior of the lamp to supply the necessary oxygen to the flame of the burner 2.

6 designates an auxiliary font provided with an annular oil-chamber 7 (see Fig. III) to hold oil introduced thereinto. The auxiliary font consists of inner and outer walls, and in the font are openings 8, through which the light from the burner 2 may pass

to be shed through the semaphore-lenses B. 50 The upper and lower portions of the auxiliary font are connected by channels 9, located between the openings 8, so that the oil in the auxiliary font may have free circulation from top to bottom thereof. Depend- 55 ing from the bottom of the auxiliary font is a leg 10, that is seated in the aperture 3 in the top of the main font and extends downwardly into said main font when the two fonts are assembled, as illustrated in Fig. III. At the 60 upper end of the leg 10 is a valve-seat 11, that is provided with an orifice 12.

13 is a valve located above the valve-seat 11 for movement to and away from said seat, the valve being directed during its movement by 65 guides 14, surmounting the valve-seat, and also by a valve-stem 15, that extends downwardly through the orifice 12 and is slidably positioned in a guide-bar 16, located within the leg 10. At the lower end of the valve-stem 70 15 is a head 17.

18 is a spring-catch secured to the main font 1 and having an upwardly-extending free end that engages the catch-pin 19, projecting from the auxiliary font to hold the two fonts assem- 75 bled when placed together.

When the fonts are to be placed in service, the auxiliary font is removed from the main font by disconnecting the catch 18 from the pin 19 and lifting the auxiliary font from the main font to withdraw the leg 10 from the opening 3 in which it rests. The main font is then filled with oil and the auxiliary font is inverted and oil is introduced thereinto through the leg 10 and orifice 12 in the valve-seat 11 to fill said font, during which action the valve 13 remains unseated to permit the inflow of the oil. The valve 13 is then drawn to its seat and the auxiliary font is turned into upright position and applied to the main font 80 by passing its leg 10 through the opening 3 in the top of said main font, and the two fonts are connected together. In assembling the fonts the lower end of the valve-stem 15 strikes against the bottom of the main font, 85 thereby elevating the valve 13 from its seat to provide for communication between the auxiliary and main fonts. During the service of 90 95

- the lamp or lantern the oil supplied to the burner 2 is at first obtained from the quantity in the main font, and the oil in the auxiliary font remains undisturbed until the oil in the 5 main font reaches a point beneath the level of the auxiliary-font leg 10 to permit ingress of air into said auxiliary font. As soon as air is thus permitted to enter the oil flows from the auxiliary font into the main font 10 through the leg 10 until it reaches the level of the lower end of said leg, at which time the leg again becomes sealed to prevent further flow until the supply in the main font is again diminished. The flow from the auxiliary font 15 to the main font is thus kept up until the oil in both of the fonts is depleted. It will be seen that I thus provide for a large supply of oil that is constantly delivered to the burner-wick, and as a result of which the lamp or lantern 20 may remain in service with one filling for a long period.

I claim as my invention—

1. The combination with the main font of a

lamp or lantern, of an auxiliary font detachably fitted to said main font and consisting of 25 inner and outer walls connected at their upper and lower ends and spaced apart to provide an annular oil-chamber; said inner and outer walls being cut out intermediate their upper and lower ends to provide a light passage-way 30 spaced from the upper and lower ends of the walls.

2. The combination with the main font of a lamp or lantern, of an auxiliary font detachably fitted to said main font and consisting of 35 inner and outer walls connected at their upper and lower ends and spaced apart to provide an annular oil-chamber; said inner and outer walls being cut out intermediate their upper and lower ends to provide a plurality of light 40 passage-ways spaced apart and spaced from the upper and lower ends of the walls.

GEO. H. ROLFES.
